Attorney

UNITED STATES PATENT OFFICE.

ZEBULON J. EURY, OF FORT WORTH, TEXAS.

METHOD OF REPAIRING SCORED CYLINDERS.

1,384,456.

Specification of Letters Patent. Patented July 12, 1921.

Application filed May 1, 1919, Serial No. 294,126. Renewed June 6, 1921. Serial No. 475,558.

To all whom it may concern:

Be it known that I, ZEBULON J. EURY, a citizen of the United States of America, residing at Forth Worth, in the county of 5 Tarrant and State of Texas, have invented certain new and useful Improvements in Methods of Repairing Scored Cylinders, of which the following is a specification.

My invention relates to improvements in 10 repairing scored cylinders and particularly for repairing scored cylinders of internal combustion engines; and the object is to provide a simple and highly efficient method of repairing scored cylinders and which will 15 make the cylinders as smooth and hard as they were originally before being scored, and to fill the scores with a composition of metal which will be as firm as the original metal of the cylinder. Other objects and 20 advantages will be fully explained in the following description and the invention will be more particularly pointed out in the claims.

Reference is had to the accompanying 25 drawings which form a part of the application.

Figure 1 is a broken section of a cylinder, showing several repairs of scores. Fig. 2 is a cross section of the repaired score at *a*. 30 Fig. 3 is a cross section of the repaired score at *b*. Fig. 4 is a cross-section of the repaired score at *c*.

Similar characters of reference are used to indicate the same parts throughout the 35 several views.

In repairing the scores, the score is made deeper and the edges are undercut, or cut so that the metal added will be dove-tailed into the surface of the cylinder as shown at 40 *a*, Figs. 1 and 2. The added metal may be melted and forced into the score by an acetylene torch. An alloy of zinc, tin, and silver may be used as hereinafter specified, and when prepared, this alloy is forced into 45 the scored portion until the metal is firmly pressed into score until the metal fills all the undercut edges. The surface of the metal is then ground smooth to conform to the contour of the interior surface of the 50 cylinder. This alloy has a high melting point and when carefully placed and anchored in the score in the manner described, the interior surface of the cylinder is as smooth as the cylinder originally appeared 55 before being scored.

Another method of anchoring the repair alloy in the cylinder is to drill out the score deeper and undercut the edges, as shown at *b*, Figs. 1 and 3. Small holes are then made through the undercut edges so that when 60 the alloy is forced into the score, the alloy will project through the openings in the overhanging edges, as illustrated in Fig. 3. After the alloy is forced into the drilled out score and through the openings to form the 65 projections *g*, the alloy is ground smooth to conform to the interior surface of the cylinder. In this manner the alloy is firmly anchored to the interior of the cylinder.

Another method of anchoring the repair 70 alloy to the cylinder is to drill out the score as shown at *c* in Figs. 1 and 4. After the score is drilled out, small cavities *h* are made in the bottom of the score, as shown at *h* in the score *d*. The alloy is then forced into 75 the score and into the cavities *h*. The alloy is then ground smooth as before. When so repaired, the alloy is firmly anchored in the score and cannot be removed by any ordinary service. Different alloys may be used, 80 such as copper, tin, and silver combined.

The composition may consist of block tin containing 2% of silver and 1% of nickel, or the same composition with $\frac{1}{2}\%$ of zinc added, or of silver solder and 1 to 2% of 85 nickel, or $\frac{1}{2}$ tin and $\frac{1}{2}$ silver solder with 8% to 8% nickel added.

Variations in the method described may be made without departing from my invention.

What I claim, is,—

1. The method herein described which consists in drilling scores in cylinders and forming undercut edges with perforations therein, forming and forcing an alloy of 95 high melting point into and filling the scores and interlocking the alloy in said perforations, and then polishing the alloy and making the same conform to the interior surface of the cylinder.

100

2. The method herein described which consists in drilling scores in cylinders with undercut edges and forming cavities in the scores, forming and forcing an alloy of high melting point by blow torch into the 105 scores and into the cavities therein for anchoring the alloy in the cavities in the scores, and then polishing the alloy to make the same conform to the interior surface of the cylinder.

110

3. The method herein described for repairing scored cylinders of internal combustion engines which consists in drilling the scores to form openings with undercut edges
5 and forming cavities therein, forming and forcing an alloy of zinc, tin, and silver by blow torch into the scores and the cavities

while in plastic condition, and then polishing the alloy to make the same conform to the interior surface of the cylinder.

In testimony whereof, I set my hand, this 28th day of April, 1919.

ZEBULON J. EURY.
